ENGINEER'S POINT FINDER

Evert W. Carlson and Vernon J. Flink,
Cambridge, Minn.

Application June 16, 1948, Serial No. 33,317

2 Claims. (CL. 33—74)

1

This invention relates to a point locator for use in general surveying and building operations.

It is an object of the invention to provide a support for a plumb line which can be conveniently and accurately located over a point which may be fixed by a transit or by means of which a previously fixed point can be readily lined up with the use of a transit or some other measuring instrument.

Another object of the invention is to provide a plumb line support with means for raising and lowering the line and holding it in various vertically adjusted positions.

Another object of the invention is to provide a plumb line support including a generally horizontally shiftable guide which is movable relative to the remainder of the support so that the plumb line can be shifted in a horizontal plane.

Still another object of the invention is to provide a readily collapsible and readily set up plumb line support in addition to means for assisting in maintaining the plumb line in a vertical position and checking its swing, said latter means also serving as a finder by means of which the plumb line can be more readily and accurately located from a distance.

The above and other objects and advantages of the invention will more fully appear from the following description made in connection with the accompanying drawing, wherein like reference characters refer to the same parts throughout the views, and, in which:

Figure 1 is a side elevational view of the apparatus;

Figure 2 is a plan view thereof;

Figure 3 is an enlarged fragmentary view partially in vertical section of the upper portion of the structure; and

Figure 4 is a section taken approximately on the line 4—4 of Figure 1.

The vertical stand or tripod includes an annular casting 5 which is supported by three legs 6 which are pointed at their lower ends so that they can be firmly set in any desired location. The upper ends of the legs 6 lie between pairs of lugs 7 which extend downwardly from the annular table member 5 and are pivotally connected to the legs by means of bolts having swing nuts 9 thereon. As a result the legs 6 can be individually placed at different angles.

The annular table 5 has a central aperture 10 shown in Figure 3. Beneath the stationary table portion 5 is an inverted cup-shaped member 11 having an upstanding central threaded post 12 upon which is screwed a disc 13. Superimposed

2

upon the disc 13 and welded thereto is a strengthening plate 13a. A shoulder 14 on the post 12 prevents the disc 13 from being turned down far enough to clamp the stationary table portion 5 between the disc 13 and the cup 11. Preferably when the disc 13 is tight on the threaded post 12 it is a close yet freely sliding fit between the stationary annular table portion 5 and the spaced cup and disc. Set screws 15 are threaded through the disc 13 and plate 13a and are adapted to bear against the stationary table portion 5 to lock the movable table portion made up of the cup and disc against shifting movement. When the set screws 15 are loosened, however, the movable table portion can be shifted in a horizontal plane.

The inverted cup 11 has a ring 16 supported therein by means of pointed set screws 17 placed at two opposite points on the side wall of the cup 11. This permits the ring 16 to tilt about the common axis of the screws 17.

Located concentrically within the ring 16 is an upright cup-shaped casting 18 which is pivotally supported between opposite points on the ring 16 by means of set screws 19 having their common axis placed at right angles to the set screws 17. This supports the cup 18 for substantially universal pivotal movement relative to the remainder of the structure. Mounted on the disc 13 is a bracket 20 whose upper portion is composed of spaced fork arms 20a between which is mounted a reel 21 on a shaft 22. The shaft 22 is provided with a small hand crank 23. One of the fork arms 20a has a thumb screw 24 threaded therethrough and adapted to engage a side of the reel 21 so that it can be releasably secured against rotation.

The upstanding post 12 on the inverted cup 11 is provided with a longitudinal vertical aperture 25 which extends down through a lower post element 26 inside the cup 11. The post 26 terminates in the inner cup 18 at a point approximately at the same level as and at the intersection of the axes of the screws 17 and 19.

Extending downwardly from the cup 18 is a tube 27 whose lower end is provided with an apertured plug 28. As shown in Figure 1, the tube 27 is provided with alternating contrasting colors as at 29 and 30. A plumb line 31 is shown wound upon the reel 21 and extending downwardly through the posts 12 and 26, the tube 27 and through the apertured plug 28 in the bottom of said tube. A plumb bob 32 is secured to the end of the plumb line 31.

The plumb line can be raised or lowered by means of the reel 21 with its handle 23 and locked

in any suitable vertical position by means of the thumb screw 24 on the reel assembly.

When the device is set up above a previously located point the tripod or stand is placed approximately over the point and leveled by proper manipulation of the independently movable legs.

6. The movable table portion comprising the disc 13 and inverted cup 11 along with the structure supported thereby is shifted horizontally on the stationary annular table ring 5 until the plumb bob 32 is located over the point as indicated in Figure 1. The thumb screws 15 can then be tightened to hold the plumb line directly over the desired point as long as needed.

The tube 27 through which the plumb line extends is relatively long and serves to quickly stop swinging movement of the plumb line and also prevents it from being swung by the wind. The depending post 26 in the cup 11 terminates at the point of intersection at the axis of the screws 17 and 19 so that even if the tube 27 is at an angle to the horizontal table elements, the plumb line will be held in the center of the tube and will hang in a proper vertical position.

If desired, the stationary annular table portion 5 can be provided with a small upright flag standard 33 upon which a warning flag 34 can be mounted so that the device can be readily seen when placed in locations such as on streets and highways and will not be damaged by traffic.

It will, of course, be understood that various changes may be made in the form, details, arrangement and proportions of the various parts without departing from the scope of our invention.

What we claim is:

1. In an engineer's point locator, an upright stand having a table at its top, a portion of said

table being substantially horizontally shiftable, a plumb line guide carried by said shiftable table portion, and a plumb line takeup device mounted on said table separate from said plumb line guide but co-operating therewith and shiftable with said table and with said guide.

2. In an engineer's point locator, an upright stand having a table at its top, a portion of said table being substantially horizontally shiftable, a plumb line guide carried by said shiftable table portion, said plumb line guide having an aperture extending throughout its entire length to accommodate a plumb line therein, a reel on said shiftable table co-operating with said plumb line guide and upon which a plumb line is adapted to be wound, and said reel having releasable locking means thereon to hold said plumb line in various extended positions.
